SIMON W. WARDWELL AND CARL A. BRINK, OF PROVIDENCE, RHODE ISLAND, AS-SIGNORS TO WARDWELL BRAIDING MACHINE COMPANY, OF PORTLAND, MAINE, A CORPORATION OF MAINE.

HOLDER FOR COP-TUBES, BOBBINS, SPOOLS, OR THE LIKE.

1,078,393.

Specification of Letters Patent. Patented Nov. 11, 1913.

Application filed March 27, 1912. Serial No. 686,519.

To all whom it may concern:

Be it known that we, SIMON W. WARDWELL and CARL A. BRINK, citizens of the United States, residing at Providence, in the county of Providence and State of Rhode Island, have invented certain new and useful Improvements in Holders for Cop-Tubes, Bobbins, Spools, or the like, of which the following is a specification.

10 Our invention relates to cop-tube, bobbin or spool holders for use with braiding, winding or other textile machines and consists of improvements in the means for securing the cop-tube, bobbin or spool on the 15 spindle to adapt it to rotate therewith.

The object of our improvement is to provide a holder adapted to receive bobbins, cop-tubes or spools having bores of varying sizes and to center them on the spindle 20 while securing them rotatively therewith.

The invention is fully set forth in the following specification, illustrated by the accompanying drawings, in which:

Figure 1 is a longitudinal view of a cop-tube holder adapted for use on braiding machines or for other purposes where the yarn is to be unwound from the cop or package; Fig. 2, an end-view of the same; Fig. 3, a transverse, sectional view of the 30 holder taken on line A—A of Fig. 1; Fig. 4, a longitudinal view of a winding spindle, showing our improvement applied thereto; Fig. 5, an end view of the same.

Referring to the drawings, in Fig. 1 we 35 have illustrated a holder designed particularly for use on braiding machines to support the rotating supply cops or bobbins from which the yarn is delivered. The same arrangement might also be used for other 40 purposes such as to unwind yarn from cops or spools in delivering it to winding or other machines employed in the various manufacturing processes.

The cop-tube holder B is mounted to rotate 45 on a dead spindle C and usually a brake-wheel or flange b is provided to control the rotation of the holder. In its present form the holder proper consists of a sleeve D which is preferably formed up from a 50 tube with its ends rounded in and crimped at d and d' to form bearings d² and d³ fitted to the spindle C. A collar or flange c is formed integral with or secured on the end of the spindle C to hold the sleeve D in

place thereon. At d the crimped portion 55 of the tube is flattened into the radially projecting ribs or splines d⁴ and d⁵, which are adapted to engage the interior of the cop-tube x, as more fully explained herein-after. At the outer end of the sleeve D the 60 tube is formed with radial ears d⁶, d⁸, which are made hollow to receive the ends e, e, of a double, wire spring E shaped something like a hairpin. Preferably, the ends of the 65 springs are secured in the ears d⁶ by crimping the metal tightly around them. The outer end of the spring E is curled over at e' to provide an abutment e² which engages the end of the cop-tube x when the latter is 70 placed in position on the holder.

The means for securing the cop-tube or bobbin rotatively on the holder consists essentially of a split sleeve F mounted on the sleeve D and having one of its longitudinally extending edges bent radially outward to form a blade adapted to indent and 75 engage the inner surface of the tube. The sleeve F is constructed with its inside diameter slightly larger than the outside diameter of the sleeve D so that it floats loosely 80 on the latter to allow it to contact and expand radially, according to variations in the bore of the cop-tube x. At its inner end the sleeve F is provided with a slot f through which one of the blades d⁴ projects; and the opposite blade d⁵ projects 85 through the longitudinal slit f' in the sleeve. The sleeve F is also slotted at f², f³ on opposite sides of its outer end to provide openings for the ears d⁶, d⁸, and the ends of 90 the slots engage the inner ends of the ears to retain the sleeve in place on the holder. The outer end of the sleeve F is preferably reduced in diameter or rounded over at f⁸ to adapt it to enter the tube easily. 95

One of the edges of the sleeve F bordering on the slit f' is bent radially outward at f³, see Fig. 2, to provide a sharp blade adapted to engage the inner surface of the cop-tube x. On the diametrically opposite side 100 from this blade f³ the sleeve F is formed up with two radially projecting, longitudinal ribs f⁴, f⁵, which are also adapted to slightly indent the inner surface of the tube x when the latter is slid onto the holder. The two 105 ribs f⁴, f⁵ and the blade f³ serve as a three-point bearing to centralize the cop-tube on the holder and the sleeve F, being spring-

tempered, will expand or contract to a slight extent to adapt it to fit tubes which vary somewhat in the size of their bores. The ribs d^4 , d^5 and the ears d^6 , engaging the slots 5 in the sleeve F, hold the latter from turning on the sleeve D and the several parts of the holder are rotated as a whole when the cop or other supply package is turned by drawing off the yarn. When the holder is used 10 for this purpose, that is, for delivering the yarn from the cop, the latter is placed on the holder so that in drawing off the yarn the tube α will turn in the direction indicated by the arrow y , Fig. 2. As the tube 15 is turned in this direction it acts to force the blade f^3 more firmly into engagement with its interior and tends to expand the whole sleeve F so that it takes a firm grip on the tube. The ribs d^4 and d^5 assist in 20 holding the tube α but are not absolutely necessary to the practical working of the device. It will be understood that the blade f^3 , acting as a dog, serves to rotate the holder and the spring E retains the tube longitudinally 25 on the holder against the action of centrifugal force when the device is revolved rapidly on the braiding machine. To remove the tube α from the holder it is only necessary to turn it in the direction opposite 30 to that indicated by the arrow y , Fig. 2, and the tendency will then be to contract the sleeve F so that the tube can be easily withdrawn therefrom, after the spring E is released. 35 In Figs. 4 and 5 we have illustrated another embodiment of the invention and shown the device applied to a live spindle adapted for use with winding, spooling or spinning machines. The holding sleeve F' 40 is here shown mounted directly on the spindle G and held rotatively therewith. The spindle G is preferably formed with a slot or keyway g extending longitudinally thereof and also with a peripheral groove g' at 45 its end. The sleeve F' is of practically the same construction as the sleeve F shown in Figs. 1 and 2, except that the means for securing it rotatively on the spindle are slightly changed. A portion of the edge of 50 the slit f' opposite to the blade f^3 is cut away and bent radially inward at f^6 to provide a feather or key adapted to engage the keyway g of the spindle and at its outer end the sleeve F' is formed with an ear f^7 , 55 also bent radially inward and adapted to engage the peripheral slot g' , see Fig. 5. The key f^6 secures the sleeve F' rotatively with the spindle G and the ear f^7 holds it longitudinally thereto. The spindle G is 60 adapted to rotate in the direction indicated by the arrow z Fig. 5, and the upturned edge of blade f^3 of the sleeve F' serves to drive the cop-tube or bobbin to wind the yarn thereon. The tension on the yarn will of 65 course create a resistance to the rotation of

the cop-tube and this acts to engage the blade f^3 more firmly with the interior of the tube and also tends to expand the sleeve F' to take a firmer grip on the bore of the tube, all as previously explained. The tube is released from the holder by turning it in the direction indicated by the arrow z to contract the sleeve F'. 70

We have illustrated the invention as used for holding the ordinary form of paper or fiber cop-tube, but it is obvious that the device is equally well adapted for holding bobbins, spools or the like which are generally constructed of wood. Owing to inaccuracies of manufacture and other causes the usual commercial form of cop-tubes, bobbins, spools, etc., vary considerably in the diameters of their bores. Furthermore, their bores are never absolutely straight and true and the wood is liable to shrink and swell. 80 The present holder is designed especially to meet these conditions and the adjustable feature of the split sleeve which receives the tube or spool adapts it to fit various sizes of bores and to conform to irregularities in the 85 bores. The spring tendency of the sleeve is sufficient to adapt it to expand to fit the tube snugly, but, on the other hand, the sleeve can contract when necessary, so that there is no danger of splitting the bobbin or spool. 90 95

In operation, the turning of the cop on the spindle or, vice versa, the turning of the spindle to rotate the cop serves to grip the tube more firmly to prevent slipping; and a reverse turn of the cop releases the holding sleeve from its engagement with the tube so that the latter cannot bind on the holder, but is easily withdrawn. This latter is an important feature, for when the cop is wound on a paper tube the constriction of 100 the coils of winding will contract the tube and make it bind on the holder so that with the ordinary devices it is often well nigh impossible to withdraw it. 105

Various modifications might be made in 110 the form and structure of our device without departing from the spirit or scope of the invention.

Therefore, without limiting ourselves to the exact construction shown, what we claim 115 is:-

1. In a holder for cop-tubes, bobbins, spools or the like, the combination with a spindle, of a split-sleeve mounted on the spindle with one of its longitudinally-extending edges formed to engage the interior surface of the cop tube to secure the latter rotatively with the holder, said sleeve adapted to be expanded by the pressure of the tube against its edge during rotation of the 120 holder to force said edge into firmer engagement with the tube.

2. In a holder for cop-tubes, bobbins, spools or the like, the combination with a spindle formed with a longitudinal slot, of 125

a longitudinally-split sleeve mounted on the spindle with one of the edges of its split portion bent radially inward and engaging the slot in the spindle to secure it relatively 5 therewith, and the opposite edge of the split portion bent radially outward to engage the interior of the cop-tube, said sleeve so arranged as to adapt it to expand radially through pressure against its outwardly-bent 10 edge to force said edge into firmer engagement with the tube.

3. In a holder for cop-tubes or the like, the combination with a spindle formed with a longitudinal slot and an annular groove, of 15 a split-sleeve mounted on said spindle and

having projections bent radially inward to engage the slot and groove, said sleeve formed with one of the edges of its split portion bent radially outward and so arranged that the pressure of the tube against 20 said edge during rotation acts to expand the sleeve to force the edge to indent the interior of the tube.

In testimony whereof we affix our signatures in presence of two witnesses.

SIMON W. WARDWELL.
